UNITED STATES PATENT OFFICE.

MICHAEL LUERY AND BEN S. NELSON, OF CHICAGO, ILLINOIS; SAID NELSON
ASSIGNOR TO MODEL FORM COMPANY, OF CHICAGO, ILLINOIS, A CORPORA-
TION OF ILLINOIS.

DRESS-FORM.

1,351,180.

Specification of Letters Patent. Patented Aug. 31, 1920.

Application filed March 19, 1917. Serial No. 155,842.

To all whom it may concern:

Be it known that we, MICHAEL LUERY and BEN S. NELSON, citizens of the United States, residing at Chicago, in the county 5 of Cook and State of Illinois, have invented new and useful Improvements in Dress-Forms, of which the following is a full, clear, concise, and exact description, reference being had to the accompanying drawing, forming a part of this specification.

Our invention relates to dress forms, an object thereof being to provide an improved and simplified construction. There are various new features in our invention, one 15 of which resides in the improved method of telescoping the form, so that the body portion drops down within the skirt and toward the base of the standard and the form thus takes up less space for storage purposes. 20 One of the improved details of construction is in the bracket for supporting the body portion upon the upright of the standard. Another feature is in the particular method of securing the skirt to the body portion so as to permit the body portion to 25 slide or telescope within the skirt.

Referring more particularly to the accompanying drawings, which illustrate our invention, we have shown various views, in 30 which—

Figure 1 is a transverse section of the preferred form of our invention with the form extended for use.

Fig. 2 is a transverse section showing the 35 form telescoped;

Fig. 3 is a bottom view of the body portion of the form, showing the body-supporting bracket more in detail; and

Fig. 4 is a perspective view of the bracket 40 slidly attaching the skirt to the body.

Referring now more particularly to the preferred form of our invention, this comprises a body portion, preferably of the adjustable type. That is, a body portion cut up into a plurality of sections, which are 45 preferably connected by yielding connectors of some well-known type. For the purpose of illustrating our invention, we have shown a connector 1 comprising a slotted 50 plate secured at one end to a section and at its other end to another section by means of a bolt and thumb nut with a spring and washer between the nut and the plate 1, so that the device yieldingly connects the adjacent sections. The hip sections of the

body portion are secured to the usual wood base pieces 2. The neck portions of the dress form are attached to overlapping clamping-plates 3, which plates are slotted and have a threaded rod 4 passing therethrough, so that they may be compressed by the nut 5 and the clamping-wheel 6 to lock the neck in the desired adjustment. The support for the body of the dress form comprises a base 7 having a standard or 60 pipe 8 threaded therein and extending upwardly to support the body portion. At the upper end of the standard 8 is a collar 9, securely fastened thereto by means of a set-screw 10, so as to rigidly hold the collar 65 9 in place. A set-screw 11 is threaded into the collar 9 and is adapted to act upon the rod 4, which supports the upper part of the body. The collar 9 is simply provided to furnish a suitable support for the set-screw 70 11. The pipe being thin, there is not sufficient material to afford suitable threads for the screw 11.

To the base-boards 2 of the body portion is secured a bracket having arms 12 slotted 75 to receive bolts 13 on which are threaded thumb nuts 14. This arm portion supports a hub 15 having a flange 16 embraced by the hook-shaped lugs 17, which are preferably integral with the arm portion. These 80 lugs are so positioned that the hub 15 may be slid into them, so that its central opening is opposite the opening in the bracket. Thus, when the standard 8 is extended 85 through the hub and bracket, they are held 90 against lateral displacement. A set-screw 18 is threaded into the hub 15 and adapted to act upon the standard 8, so that the bracket may be moved up and down thereon. In order to move the form up and down on 95 the standard, it is necessary that both set-screws 11 and 18 be loose, so that the rod 4 may slide down within the pipe 8 and the hub and bracket down on the outside of the pipe. If the screw 18 only is loosened and 100 the screw 11 left tight, it will be apparent that the rod 4 cannot be moved, although the bottom half of the body portion might be moved vertically to extend or contract the form vertically. This will be referred to 105 more in detail in a subsequent portion of the specification. If the set-screw 18 is tightened and the set-screw 11 loosened, then the rod 4 is movable within the pipe 8 and thus the upper portion of the form may be 110

pressed downwardly toward the base portion of the body, as is the case when the form has been adjusted.

Ordinarily in the use of the form the set-screw 18 is maintained tightened and the set-screw 11 loose. In this condition the hub 15 of the bracket is rigidly held against the pipe 8, but the arm portions of the bracket are free to rotate, so that the body and skirt of the form may be rotated without rotating the base 7. This, of course, is an advantage, in that when working upon a dress supported by the form the dress-maker may readily rotate the form without 10 rotating the base. The broad idea of arranging the form so that it may be rotated on the standard is not new. In previous forms various kinds of brackets have been used which permit of this rotation. In 15 some of these brackets the hub was riveted to the arm portions or secured by set-screws, so as to permit relative rotation, but the machining necessary for this construction was found comparatively expensive. Another 20 objection to previous brackets where machining was necessary was that considerable breakage occurred. Where rivets were provided to secure the parts together, the parts were frequently broken in driving the rivet into the casting. Where screws 25 were used, the taps were frequently broken. To eliminate this machining and breakage was one of the ends we had in view. In our present bracket no machining is necessary, as the castings 15 and 12 are assembled by 30 simply sliding the hub 15 beneath the lugs 17. Thus, a cheap and comparatively simple revolvable bracket is provided.

The preferred form of skirt used in connection with the present invention is that shown in the drawings and comprises a ribbon-like structure, including vertical strips 19 of a suitable number, riveted together by horizontal strips 20. The skirt is made 35 in sections corresponding in number to the number of hip sections to the body. In the present form there are four sections. The sections are secured together at their dividing point by means of pivoted connectors 21. Adjacent each vertical strip 19 is a corresponding supporting strip 22, which is riveted at each end to the cross-piece 20. For supporting the skirt we provide brackets 23 having engaging portions 24 bent to correspond to the strip 22, embracing the same so as to permit a free vertical movement of the strip 22. This bent part 24 is fastened to the bracket 23 by means of a suitable rivet 25. In assembling the bracket 23 and 50 the skirt, the bent portion 24 is slid over the strip 22 before the strip is attached at its ends to the skirt. Thereafter, the bracket 23 is secured to the base-boards 2 by means of screws passing through the holes 26. 55 Thus, the skirt may be slid up and down so

as to telescope with the body portion, as shown in Fig. 2.

In the use of the dress form in its extended position as shown in Fig. 1, the set-screw 18 is ordinarily maintained tightened 70 and the set-screw 11 loose. To adjust the body portion the clamping-wheel 6 is first loosened. The thumb-nuts 14 at the base-boards of the form are also loosened, although ordinarily it is not necessary to 75 tighten these thumb nuts. The operator may then grasp the sections and adjust the form into the desired shape, due to the yielding or spring-pressed connections 1. After the body portion has been adjusted, 80 the wheel 6 is fastened and also the thumb nuts 14 if desired. Due to the rotatable connection between the hub 15 and the arms 12 of the bracket, it will be seen that the dress form may be rotated about the base 7; 85 that is, although the hub 15 is rigidly secured to the standard 8 of the base, due to the swivel connection between the hub and the bracket the form is free to be rotated, because the set-screw 11 is not tightened. If the set-screw 11 is tightened it will be 90 apparent that the rod 4 is held secure to the standard of the base, and therefore rotation of the form upon its base is prevented.

Should the operator desire to compress or 95 close the body portion of the form as shown in Fig. 2, the set-screw 18 being tightened and the set-screw 11 loose, it is only necessary to place the hands upon the shoulders of the body portion and press downwardly. This does not move the entire body downwardly upon the standard, because the set-screw 18 is tightened, but simply moves the shoulder and the bust portions of the form 100 downwardly until they engage the hip sections, as shown in Fig. 2.

Now if it is desired to drop the body portion over the standard of the base, the operator loosens the set-screw 18, thus permitting the hub 15 of the bracket 12 to slide down over the standard 8, as shown in Fig. 2. Before dropping the body down, the operator may grasp the skirt and move it upwardly to telescope over the body, as shown 105 in Fig. 2, or the skirt may be permitted to engage the legs of the base as the body is dropped, the continued downward movement of the body causing the skirt to telescope over the body, as shown in Fig. 2.

To extend the dress form, and assuming 110 it is closed or telescoped, as shown in Fig. 2, the operator first sees that the set-screw 18 is loose and then grasps the form at a suitable place, such as in the arm-holes or by the wheel 6, and lifts the body upwardly to 115 a suitable height and then fastens the set-screw 18. The skirt may then be pulled downwardly into the position shown in Fig. 1, the supporting strips 22 sliding in the 120 holders 24 of the supporting bracket. If 125 130

the body portion is adjustable, it may now be adjusted to suitable dimensions if desired.

In illustrating our invention, we have shown an adjustable body portion, but it is to be understood that so far as some features of our invention are concerned they may be used with a non-adjustable body portion. It is also to be understood that we contemplate applying our invention in various other ways than that shown, and it will be apparent that various changes and modifications will readily occur to those skilled in the art, and therefore we do not desire to be limited to the exact structure shown and described, but aim to cover all that which comes within the spirit and scope of the appended claims.

What we claim as new and desire to secure by Letters Patent is:—

1. A dress form comprising a base, a tubular standard extending upwardly from and fixed to the base, an adjustable body, a bracket secured to the base of the body and adjustably embracing the standard so that the body may be dropped down to the base into a compact arrangement, and a guide rod secured to the neck of the body and extend-

ing downwardly into the standard so as to support the body but permit reducing it by pressing down upon the shoulders. 30

2. A bracket for dress forms comprising a laterally extending body-supporting arm portion, having a central opening, a flanged hub, and hook-shaped lugs for the arm portion positioned to permit sliding the flange 35 of the hub therein to effect registration of the arm and hub openings.

3. A bracket for dress forms comprising laterally extending body-supporting arms, a central disk connecting the arms and provided with a standard opening, an annular flanged hub, and hook shaped retaining means on the disk positioned to permit laterally sliding the hub-flange therein to effect registration of the flange and disk openings 45 whereby the hub and disk are held against relative lateral and longitudinal movement when the standard is inserted through the hub and disk.

In witness whereof, we have hereunto subscribed our names. 50

MICHAEL LUERY.
BEN S. NELSON.
